UNITED STATES PATENT OFFICE.

J. MILTON HAMMILL, OF PHILADELPHIA, PENNSYLVANIA.

COVERING FOR STEAM-PIPES.

SPECIFICATION forming part of Letters Patent No. 311,750, dated February 3, 1885.

Application filed March 3, 1884. (Model.)

To all whom it may concern:

Be it known that I, J. MILTON HAMMILL, a citizen of the United States, residing in Philadelphia, Pennsylvania, have invented 5 certain Improvements in Non-Conducting Coverings for Steam-Pipes, &c., of which the following is a specification.

My invention consists of an improved form of non-conducting covering for steam-pipes, 10 to boilers, and other surfaces, as more fully described hereinafter.

The main feature of my invention consists in constructing the covering of a series of superposed layers of backing having applied 15 thereto, by an adhesive material, a facing or facings of granulated cork, which, while itself a non-conductor, will leave open passages between the layers, allowing a free circulation of air through them.

20 In the accompanying drawings, Figure 1 is a transverse section of a steam-pipe with my improved covering applied thereto. Fig. 2 is a perspective view illustrating the construction of the covering and its application 25 to the pipe, and Fig. 3 is an end view of a section of covering ready to be applied.

A is the steam-pipe or other surface to be covered, and B is the covering, which consists, essentially, of a series of superposed layers of 30 paper, straw-board, or muslin, or similar backing, b, having applied to one or both of its faces, with shellac or any suitable cement, a facing or coating, b', of suitable thickness, of granulated cork or equivalent material. The 35 backing b is first prepared with its granulated facing or facings b', and when it is to be applied to piping may then be wound in spiral or sepa-

rate layers directly on the pipe itself or on a mandrel, the layers being united, so far as desirable, by cement. When the layers are 40 wound on a separate mandrel, they are formed into sections of covering B of suitable length, and split longitudinally for application to the pipe. When they are to be applied to other surfaces, the superposed layers may be formed 45 into blocks of suitable size.

It will be seen that while the material of the granular surface is itself a good non-conductor, one of its main advantages is that it forms tortuous passages between the layers for the 50 circulation of air, such passages being of a very open character, such as could not be obtained if the granulated material were separate from the backing.

I prefer to combine with the covering B an 55 outer coating, a', of asbestos paper or suitable material, and where the pipe A or other surface to be covered is to be subjected to excessive heat an intermediate layer, a, of asbestos paper may be used. 60

I claim as my invention—

A non-conductor covering for steam-pipes and similar surfaces, said covering consisting of superposed layers of paper or other material having granulated cork adhesively applied 65 to its surface, substantially as set forth.

In testimony whereof I have signed my name to this specification in the presence of two subscribing witnesses.

J. MILTON HAMMILL.
